UNITED STATES PATENT OFFICE.

ALICE MONTGOMERY, OF MENLO PARK, AND FLORENCE K. REYNOLDS, OF SAN FRANCISCO, CALIFORNIA.

DESIGN FOR A DOLL.

51,349.

Specification for Design.

Patented Oct. 9, 1917.

Application filed May 14, 1917. Serial No. 168,615. Term of patent 3½ years.

To all whom it may concern:

Be it known that we, ALICE MONTGOMERY and FLORENCE K. REYNOLDS, both citizens of the United States, and residents of Menlo Park, San Mateo county, California, and the city and county of San Francisco, State of California, respectively, have invented a new, original, and ornamental Design for a Doll, of which the following is a specification, reference being had to the accompanying drawing, forming part thereof.

The ornamental design for a doll, as shown.

A. MONTGOMERY.
F. K. REYNOLDS.
